UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS.

FEED AND LITTER CARRIER.

No. 888,878.

Specification of Letters Patent.

Patented May 26, 1908.

Application filed December 11, 1907. Serial No. 406,015.

To all whom it may concern:

Be it known that I, HENRY L. FERRIS, a citizen of the United States, residing at Harvard, in the county of McHenry and State of Illinois, have invented a new and useful Improvement in Feed and Litter Carriers, of which the following is a specification.

My invention relates to certain new and useful improvements in feed and litter carriers, and is fully described and explained in the specification and shown in the accompanying drawings, in which:

Figure 1 is an elevation of my improved device showing the same in position upon a track; Fig. 2 is a central longitudinal section through one of the hangers and parts adjacent thereto; Fig. 3 is an end view of the parts shown in Fig. 2 looking from the left as seen in Fig. 2; Fig. 4 is a central longitudinal section through the container and its supporting frame showing the tripping device in one position; and Fig. 5 is a similar section showing the tripping device in a different position.

The feed and litter carrier herein shown, described and explained is substantially the same as that shown and described in my application filed March 18th, 1907, Serial No. 362,990, in which application a requirement for division has been made. The claims to the general construction and arrangement of the carrier and its hoisting means have been divided out of the foregoing application. In addition to the aforesaid divisional matter the feed and litter carrier herein described embodies a container locking and tripping device which is an improvement upon that shown, described and claimed in my application filed March 18th, 1907, Serial No. 362,989, and this portion of the device is covered by certain of the claims of the last mentioned application.

Referring to the drawings, A is a suitable track which in the form of construction herein illustrated, is composed of two angle irons with the angles at the lower adjacent corners, bolted together so as to form two substantially horizontal webs and an upwardly extending central slotted portion. Upon the track A run pulleys b arranged in pairs and mounted upon the two horizontal webs of the track, the said pulleys being secured in position in hangers B which may be of any desired form and are suitable for sur-

rounding the track A. Swiveled to the hangers B are journaled C, C¹ between which extends a rotatable shaft D preferably constructed of tubing for the sake of strength and lightness. On one end of the shaft D is mounted a gear E freely rotatable with respect to the shaft and held against longitudinal displacement thereon by engagement with the hanger C to one side, and with a pin e running in an annular groove upon the gear to the other side, the pin being securely fastened to the shaft as indicated in Fig. 2. The gear E meshes with a worm E¹ secured to a counter-shaft e¹ extending transversely with respect to the shaft D, and journaled in suitable brackets provided to receive it upon the hanger B. To one end of the shaft e¹ is secured a sheave F over which runs a continuous loop of chain or other flexible material F¹. It will be obvious that by drawing the loop F¹ continuously in one direction, the sheave F will be rotated with consequent rotation of the gear E through the medium of the worm E¹. Reverse action, *i. e.* rotation of the sheave by pressure exerted upon the gears is readily prevented by properly arranging the pitch of the worm and gear.

In order to secure a rotation of the shaft D when the gear E is rotated I secure to the shaft D a longitudinally movable clutch-collar G secured against rotation with respect to the shaft by means of a pin g passing through a slot in the shaft. The face of the clutch-collar adjacent to the gear E is formed with projections adapted to engage with corresponding depressions in the face of the gear, all formed in the ordinary way common in such devices. Pivoted to the bracket in which the worm E¹ is journaled, is a bell-crank lever G¹, having a horizontal arm and a vertical arm, the horizontal arm having secured to its extremity a chain g¹ by which the bell-crank lever can be rotated. The vertical arm of the bell-crank is bifurcated and carries upon its upper end pins which run in an annular groove upon the clutch-collar G. The bell-crank lever G¹ is normally held, by means of a spring g², in such position as to hold the clutch-collar G in engagement with the gear E so that the shaft and gear will normally rotate together, but the shaft can be disengaged from the gear at any time by drawing down upon the chain g¹. As a matter of convenience I utilize the chain g¹ as an

anchoring chain and for this purpose I secure to it an anchoring hook g^3 which can engage with one of the webs of the track and when in such engagement will prevent longitudinal movement of the carrier along the track, any pressure exerted by the carrier upon the bell-crank lever at such times being a horizontal or substantially a horizontal pull which will not tend to rotate the bell-crank and disengage the clutch.

H indicates the container of my improved feed and litter carrier, the same being pivotally supported in unstable equilibrium in an inverted U shaped frame H^1 . Locking means 15 for holding the container in an upright position are provided, the said locking-means in the preferred form of construction, which is herein illustrated, being in the form of an improvement upon that shown, described and 20 claimed in my application filed March 18th, 1907, Serial No. 362989 above identified. This locking-mechanism is fully illustrated in Figs. 4 and 5 and will presently be described in detail.

The frame H^1 has at its upper corner two pulleys h . Chains I , I^1 run over these pulleys, the chain I being fastened to an eye i fast upon the shaft D at one end and having its opposite end secured to a collar i^1 rotatable 30 upon the said shaft but held against longitudinal movement thereon, and the chain I^1 having one end stationarily secured to an eye i^2 upon the shaft D and having its opposite end secured to an eye in the journal C^1 . Thus when the shaft D is rotated by the 35 means already described, the two left-hand ends of the chain I , I^1 will be wound up upon said shaft so that the frame H^1 in container H will be raised. When raised these parts 40 will stay in any desired position by reason of the use of the worm and gear as one of the elements of the hoisting means and the same can readily be lowered by throwing out the clutch to permit the shaft to rotate in a 45 reversed direction. The right-hand ends or links of the chain will not be wound up so that the shaft will have a double leverage upon the container.

Referring now to Figs. 4 and 5 it will be 50 seen that the frame H^1 has projecting laterally from it above the pivots of the container a pair of brackets j , j^1 to which are pivoted catch levers J , J^1 , of the first order, the inner ends of the aforesaid levers projecting 55 through slots in the frame H^1 and engaging notches upon projections j^2 , j^3 , on the sides of the container. This engagement takes place when the inner ends of the levers are in their upper position and the outer ends of the levers are in their lower position as shown in 60 Fig. 4. A point upon the lever J inside the pivot thereof is connected by a chain J^2 to a point on the lever J^1 outside the pivot thereof. The aforesaid chain runs in the channel 65 of the frame H^1 , which said frame is prefer-

ably constructed of oppositely facing channel iron as illustrated, and by means of the chain the two levers are caused to move simultaneously in corresponding directions, *i. e.* they are both caused to raise and to lower their inner ends simultaneously. The two levers are held normally in the position shown in Fig. 4 by means of a spring J^3 connecting the frame H^1 with a point on the lever J^1 inside its pivot, the said spring being adapted to normally draw the inner end of said lever upward. The outer end of the lever J is bifurcated after the manner of the bifurcation of the trip-arm H of my application 70 No. 362,989.

Longitudinally movable upon the track A is a trip support K in the form of a sheet-metal frame adapted to engage with the track. A chain K^1 extends downward from the trip-support to a point below the lowest 80 normal position of the lever J . A stop is provided at the lower end of the chain K^1 , preferably a hook k , and above this stop is a spring K^2 upon which rests a tripping-member K^3 in the form of a flat disk movable vertically upon the chain K^1 .

The operation of the tripping mechanism can now be set forth and it will be readily understood from the foregoing description of its mechanical construction. The common practice in using these feed and litter carriers is to push them forcibly out of the barn so as to give them sufficient momentum to reach the dumping ground without the use of further power. At the point where it 95 is desired to have them dump automatically, *i. e.* at a point ordinarily just over the wagon in which they are to dump or just over the litter pile, the trip support K is placed. As the carrier moves along on the track its forward hanger will run over the trip support K , the chain K^1 passing through the hanger. This will of course raise the tripping-member K^3 so as to pull it up against the lower surface of the bifurcated lever J as illustrated 100 in Fig. 5, the said bifurcated lever being placed in such position with respect to the hanger that the chain K^1 will pass between the furcations of said lever. The raising of 105 the said lever will lower the inner end thereof and release the container causing the contents to dump. Any remaining momentum of the carrier will be taken up in compressing the spring K^2 and to a certain extent by the spring J^3 , and as soon as the carrier has 110 dumped and the momentum has been completely absorbed by these springs, the springs will give back the impetus they have absorbed and start the carrier back upon its return journey automatically. When it is 115 desired to adjust the height of the carrier, the height of the tripping member can be 120 varied by simply looping up the lower end of the chain K^1 and engaging the hook k with one of the higher links thereof, the spring 125 130

and tripping-member being simultaneously moved upward.

It will be seen that the foregoing operation of the tripping-member is substantially the same as that set forth in my application Serial No. 362,989, but the device is simpler in construction and that it has the further advantage of providing a lock for the two ends of the carrier, which lock is simultaneously operated through very simple mechanism. I am aware that it has heretofore been proposed to apply locking means to the two ends of the container in carriers of this sort but the particular construction and arrangement herein shown is highly advantageous, especially in the use of a chain running in the channel of the frame for connecting the locks together.

I realize that considerable variation is possible in the details of construction of my improved device, without departing from the spirit of my invention, and I do not intend therefore, to limit myself to the specific form herein shown and described.

25. What I claim as new and desire to secure by Letters Patent, is—

1. The combination with a track, hangers upon the track and journals supported by the hangers, of a shaft rotatable between 30 said journals, a gear loose upon said shaft, a worm in mesh with said gear, means for rotating said worm, a clutch member non-rotatably supported upon said shaft, and adapted to engage with said gear, a container, a connection between said container and shaft whereby the rotation of said shaft will raise said container.

2. The combination with a track, hangers upon the track and journals supported by 40 the hangers, of a shaft rotatably mounted in said journals and extending between the same, a gear loose upon the shaft, a worm in mesh with said gear, means for rotating said worm, a clutch member non-rotatably supported on such shaft and adapted to engage 45 said gear, means for normally holding said clutch member in engagement with said gear, means for disengaging said clutch member and gear, a container, and connections between said container and said shaft whereby the rotation of said shaft will raise said container.

3. The combination with a track, hangers upon the track and journals supported by 55 the hangers, of a shaft rotatably mounted in said journals and extending between the same, a gear loose on the shaft, a worm in mesh with the gear, means for rotating said worm, a clutch member non-rotatably supported on said shaft adapted to engage said gear, means for normally holding said clutch member in engagement with said gear, a bell-crank lever pivoted to said journal and engaging said clutch member to release the 60 same, a container and connections between

said container and shaft whereby rotation of the shaft will raise and lower said container.

4. The combination with a track, hangers upon the track and journals supported by 70 said hangers, of a shaft rotatably mounted between said journals, means for rotating said shaft, a container, pulleys supporting the container, and connections from said shaft running over said pulleys and back to 75 non-rotatable supports.

5. The combination with a track, hangers upon the track and journals supported by the hangers, of a shaft rotatably mounted between said journals, means for rotating 80 said shaft, a container, pulleys supporting said container and connections running in bights from points upon said shaft to non-rotating supports separated laterally in the same direction from said points upon said 85 shaft, said pulleys being supported by said bights.

6. The combination with a track, hangers upon the track and a rotatable shaft supported by the hanger, of a container, connections between the container and the shaft whereby rotation of the shaft will raise the container, a gear loose upon said shaft and a worm in mesh with said gear, means for rotating said worm and a clutch member non- 95 rotatably supported upon said shaft and adapted to engage with said gear.

7. The combination with a track, hangers upon the track and a rotatable shaft supported by the hanger, of a container, connections between the container and the shaft whereby rotation of the shaft will raise the container, a gear loose upon said shaft, a worm in mesh with said gear, means for rotating said worm and a clutch member non- 100 rotatably supported upon said shaft and adapted to engage with said gear, and means for disengaging said clutch member from said gear and applying a resistance to the rotation of the shaft.

8. In a device of the class described, the combination of a yoke-shaped frame and a container pivoted therein, with two catches mounted upon opposite ends of the frame and adapted to engage the container to support the same, and means connecting said catches and constructed and arranged so that one operates the other.

9. In a device of the class described, the combination of a yoke-shaped frame and a 120 container pivoted therein, with two catches mounted upon opposite ends of the frame and adapted to engage the container to support the same, and flexible means connecting said catches and following the course of said 125 yoke-shaped frame and so constructed and arranged that one catch operates the other.

10. The combination with a yoke-shaped frame and a container pivotally supported between the ends thereof, of two catch levers 130

of the first order, pivotally supported by the ends of the frame and adapted to engage the container at opposite ends, flexible means of connection between the catches running from 5 opposite sides of the pivots thereof whereby they move in corresponding operative direction, the said flexible connector following the course of the frame, and means for normally holding one of said catches in engaging position.

10 11. The combination with a yoke-shaped frame of outwardly facing channel iron and a container pivoted between the ends thereof, of two catch levers pivoted to opposite ends 15 of the frame and adapted to engage the container at the opposite ends thereof and flexible means of connection between said catches running in a channel of the frame and constructed and arranged to cause said catches 20 to move simultaneously in corresponding operative direction.

12. The combination with a track of hangers running upon the track, a container supported by the hangers and movable longitudinally upon the track therewith, a lever of the first order pivotally supported and adapted to engage directly with the container with one end and having its opposite end bifurcated, a flexible member depending 30 from the track, a trip-member supported by said flexible member and adapted to engage said bifurcated end of said lever, when the container reaches a predetermined point upon the track whereby further movement 35 of the container will operate said lever to release the container.

13. The combination with a track of hangers running upon the track, a container supported by the hangers and movable longitudinally upon the track therewith, two locking devices, one at each end of the container, and adapted to lock the same in an upright position, means of connection between said locking devices whereby one operates the 45 other, a flexible member depending from the track, and a trip-member supported by said flexible member and adapted to engage one of the locking devices when the container reaches a predetermined point upon the 50 track whereby further movement of the container will operate the locking devices.

14. The combination with a track, of hangers supported by the track, a frame supported by the hangers, a container pivoted

to the frame, catches mounted upon the frame upon opposite ends and adapted to engage the container, means of connection between the catches so constructed and arranged that one operates the other, a flexible member depending from the track, and a trip-member carried by said flexible member and adapted to engage one of the catches.

15. The combination with a track, hangers supported by the track, a frame supported by the hangers, a container pivoted to the frame, and two catches mounted upon the frame and adapted to engage opposite ends of the container, one of said catches having a bifurcated end, and means of connection between the catches so constructed 70 and arranged that one operates the other, of a flexible member depending from the track, and a trip-member carried by said flexible member and adapted to engage the bifurcated end of said catch.

75 16. The combination with a track, hangers supported by the track, a frame supported by the hangers, a container pivoted in the frame, catch levers pivoted to the frame at opposite ends thereof and adapted to engage the container, flexible means of connection between said catches following the general course of the frame, and so constructed and arranged that one catch operates the other, and a bifurcated projection upon one of said 80 catches, of a flexible member depending from said track and a trip-member carried by said flexible member and adapted to engage said bifurcated end.

17. A combination with a track, hangers supported by the track, a yoke-shaped frame of outwardly facing channel iron supported by the hangers, a container pivoted between the ends of the frame, a catch lever pivoted at each end of the frame and engaging the 90 container, a flexible connection between the catches lying in the channel of the frame and so constructed and arranged that one catch operates the other, a bifurcated portion on one of said catches, a flexible member depending from the track, and a trip-member carried by said flexible member and adapted to engage said bifurcated fork.

100 HENRY L. FERRIS.

In presence of:

RALPH SCHAEFER,
W. F. JONES.
